(63) Continuation of application No. 11/687,085, filed on Mar. 16, 2007, now Pat. No. 7,577,372.

An image forming apparatus of the invention conveys paper fed by a paper feeding mechanism piece by piece to a paper discharging unit through a paper conveying path. An image forming unit is arranged in a midway portion of this paper conveying path and executes an image forming process for printing an image based on image data on paper being conveyed. A sensor that detects a type of the paper conveyed is arranged on an upstream side with respect to the image forming unit on the paper conveying path. Image forming process conditions for the image forming unit are set in accordance with a detection result of the sensor. When the paper fed to the paper conveying path is paper not detected by the sensor, the image forming process is started awaiting a detection result by the sensor. On the other hand, when the paper is detected by the sensor, the image forming process is started without awaiting paper type detection. Moreover, paper being conveyed is conveyed to the image forming unit, in which the image forming process is started, in synchronization with a printing operation of the image forming unit.

IMAGE FORMING APPARATUS AND
CONTROL METHOD THEREOFCROSSREFERENCE TO RELATED
APPLICATION

This application is a Continuation of application Ser. No. 11/687,085 filed on Mar. 16, 2007, the entire contents of which are incorporated herein by reference.

BACKGROUND OF THE INVENTION

1. Field of the Invention

The present invention relates to image forming apparatuses that can print characters and figures on various kinds of paper such as a printer and a copying machine and a control method thereof.

2. Description of the Related Art

In general, in this type of image forming apparatuses, printing on various kinds of paper having different thicknesses and the like is possible. However, a difference in a paper type affects transferability, fixability, and the like in printing. Therefore, for example, in an image forming apparatus of an electrophotographic system, improvement in an image quality is realized by, for example, changing a quantity of toner for transferring an image to paper, transfer conditions, and fixing conditions according to paper thickness.

Conventionally, an operator visually checks and manually designates paper type information such as thickness. However, for example, because this work is extremely complicated, it is proposed to automatically detect a paper type using a transmission optical sensor or the like.

For example, in JP-A-2004-277057, paper feeding mechanism that feeds paper piece by piece is provided for each paper feeding cassette that stacks and holds paper and, on an outgoing side of the paper feeding mechanism, a paper type sensor that detects type (thickness, etc.) of paper fed by this paper feeding mechanism is provided. In preparation for printing to be performed later, a leading end of one piece of paper at the top is fed from the paper feeding cassette by a predetermined quantity by the paper feeding mechanism at timing prior to an original paper feeding command and a type of the paper is detected by the paper type sensor.

In this way, it is possible to acquire paper type information at the timing prior to the original paper feeding command. This makes it possible to perform, for an image forming process of an image forming unit, proper setting using the detected paper type information before the paper feeding command for printing is received.

In this type of image forming apparatuses, in general, plural paper feeding cassettes as paper supplying sources are provided. Pieces of paper of types different from one another are often provided in the plural paper feeding cassettes, respectively, to make it possible to select a desired paper type from these paper feeding cassettes and perform printing. In this case, pieces of paper fed from the respective paper feeding cassettes by paper feeding mechanisms are separately joined to a common paper conveying path leading to the image forming unit, and sent to the image forming unit and printed, respectively.

A case in which the conventional technique described above is applied to such image forming apparatuses will be examined. For example, it is assumed that paper is stored in a paper feeding cassette and the paper feeding cassette is set in an image forming apparatus main body. In this case, to detect a paper type in advance in preparation for printing after this, as described above, a leading end of one piece of paper is fed

2

from the paper feeding cassette by a predetermined quantity by the paper feeding mechanism and a type of the paper is detected by the paper type sensor. Thereafter, if an original paper feeding command for the paper, the type of which is detected, is continuously issued, no problem occurs because it is possible to send the paper fed halfway to the image forming unit as it is. However, if an original paper feeding command for paper stored in another paper feeding cassette is issued, it is likely that the paper, the type of which is detected, hinders feeding and conveyance of the paper according to the original paper feeding command.

In short, in the image forming apparatus having the plural paper feeding cassettes, it is not definitely decided to which one of the paper feeding cassettes (paper types) an original paper feeding command is given. The paper feeding cassette is changed according to a print request. Therefore, as described above, it often occurs that, after a paper type of a paper feeding cassette set anew is detected, an original paper feeding command is given to another paper feeding cassette.

In this case, since the paper, the type of which is detected, stays in a state in which the leading end thereof is fed by the predetermined quantity, it is likely that the paper hinders movement of paper fed from another paper feeding cassette to a common conveying path. To prevent the paper from hindering the movement of another piece of paper, it is necessary to provide the paper type sensor in an extremely narrow portion near the paper feeding mechanism and arrange and set the paper type sensor such that the leading end of the paper in the type detected state does not project over the conveying path of another piece of paper. Therefore, the paper type sensor is subjected to restriction in terms of arrangement. Even if the paper type sensor is arranged in this way, when a quantity of paper feeding by the paper feeding mechanism is unstable, the leading end may project to the common conveying path and interfere with the movement of another piece of paper. When double feeding occurs, remaining paper may project to the common conveying path.

To surely prevent such interference, paper once fed to the sensor portion only has to be returned into the paper feeding cassette after the detection by the sensor.

However, to return the paper partially fed from the paper feeding cassette into the paper feeding cassette after the paper type detection, a complicated mechanism is required, which causes a failure. It is not preferable to return the paper once fed because a burden on the paper is heavy and a jam is caused.

Providing the paper type sensor near the paper feeding mechanism leads to misdetection of a paper type as well. The paper feeding mechanism takes out uppermost paper of paper stacked and held in the paper feeding cassette with a pickup roller and separates and feeds the paper piece by piece with a paper feeding roller arranged on a front side of the paper and a separation roller arranged on a rear side of the paper. However, when a separating action is not sufficient, two pieces of paper may be delivered together right behind the paper feeding roller and the separation roller. Even if the two pieces of paper are delivered together, in most cases, only one piece of paper is delivered to the conveying path by an action of the separation roller. However, when the paper type sensor is provided near the separation and paper feeding mechanisms,

the paper type sensor detects these two pieces of paper. Thus, for example, in the case of a sensor that detects paper thickness, misdetection is caused.

SUMMARY OF THE INVENTION

It is an object of the invention to provide an image forming apparatus that can perform printing under optimum conditions according to a paper type and without deteriorating performance because the image forming apparatus incorporates paper type detection in an image processing algorithm and controls the paper type detection to detect a paper type in the middle of paper feeding and conveyance, set an image process according to a result of the detection, and start this image forming process.

According to an aspect of the invention, an image forming apparatus includes: a paper feeding mechanism that feeds paper piece by piece; a paper conveying path that conveys paper fed by this paper feeding mechanism to a paper discharging unit; an image forming unit that is arranged between the paper feeding mechanism and the paper discharging unit on this paper conveying path and executes an image forming process for forming an image based on image data and printing the image on the paper being conveyed by the paper conveying path; a sensor that is arranged on an upstream side with respect to the image forming unit on the paper conveying path and detects a type of paper conveyed by this paper conveying path; a condition setting unit that sets conditions for an image forming process of the image forming unit in accordance with a detection result of this sensor; an image-forming-process control unit that starts the image forming process of the image forming unit awaiting the detection result of the sensor when the paper fed to the paper conveying path by the paper feeding mechanism is paper not detected by the sensor and starts the image forming process without awaiting paper type detection when the paper fed to the paper conveying path is detected by the sensor; and a paper-conveying-path control unit that causes the paper conveying path to convey paper conveyed by the paper conveying path to the image forming unit, in which the image forming process is started, in synchronization with a printing operation of the image forming unit.

According to another aspect of the invention, a control method of an image forming apparatus includes: a step of feeding paper piece by piece to a paper conveying path that conveys fed paper to a paper discharging unit; a step of detecting a type of the paper fed to the paper conveying path with a sensor; a step of setting, in accordance with a detection result of the sensor, image forming process conditions for an image forming unit that executes an image forming process for forming an image based on image data and printing the image on paper being conveyed by the paper conveying path; a step of starting the image forming process of the image forming unit awaiting a detection result by the sensor when the paper fed to the paper conveying path by the paper feeding mechanism is paper, a paper type of which is not detected by the sensor, and starting the image forming process without awaiting the paper type detection when the paper fed to the paper conveying path is paper, a type of which is detected by the sensor; and a step of conveying the paper conveyed by the paper conveying path to the image forming unit, in which the

image forming process is started, in synchronization with a printing operation of the image forming unit.

BRIEF DESCRIPTION OF THE DRAWINGS

FIG. 1 is a diagram showing an overall structure of an image detecting apparatus according to a first embodiment of the invention;

10 FIG. 2 is a functional block diagram for explaining a control unit of the image detecting apparatus according to the first embodiment of the invention;

15 FIG. 3 is a partially enlarged view for explaining a sensor setting state in the first embodiment of the invention; and

15 FIG. 4 is a partially enlarged view for explaining a sensor setting state in a second embodiment of the invention.

DETAILED DESCRIPTION OF THE INVENTION

20 Embodiments of the invention will be hereinafter explained in detail with the accompanying drawings as examples.

25 FIG. 1 shows a structure of an image forming apparatus according to a first embodiment of the invention. FIG. 2 shows control unit of the image forming apparatus as functional blocks. In FIG. 1, reference numeral 1 denotes an apparatus main body. A transparent original stand (a glass plate) 2 for placing an original is provided in an upper part of the apparatus main body 1. A cover 3 is provided on this original stand 2 to be freely opened and closed. A carriage 4 is provided on a lower surface side of the original stand 2. An exposure lamp 5 is provided in the carriage 4. The carriage 4 is capable of reciprocatingly moving along the lower surface of the original stand 2. This carriage 4 reciprocatingly moves while lighting the exposure lamp 5 to expose an original on the original stand 2. A reflected light image of the original placed on the original stand 2 is obtained by this exposure. The reflected light image is projected on a CCD (Charge Coupled Device) 10 by reflecting mirrors 6, 7, and 8 and a lens block for magnification 9. The CCD 10 outputs an image signal corresponding to the reflected light image of the original.

35 45 A scan unit (203 in FIG. 2) that optically scans an image of the original placed on the original stand 2 is constituted by the carriage 4, the exposure lamp 5, the reflecting mirrors 6, 7, and 8, the lens block for magnification 9, and the CCD 10.

50 Reference numeral 220 denotes an image forming unit, which is constituted by a print engine (213 in FIG. 2) constituted by an exposing unit 11 and the like, photoconductive drums 21, 22, 23, and 24, a transfer belt 25, a drive roller 26, and a process unit (214 in FIG. 2) constituted by a transfer-roller driving unit and the like. This image forming unit 220 forms an image based on image data (the image signal outputted from the CCD 10) and executes an image forming process for printing the image on paper being conveyed. The 55 image signal outputted from the CCD 10 is supplied to the exposing unit 11 first after being appropriately processed. The exposing unit 11 emits a laser beam B1 corresponding to an image signal of a yellow color, a laser beam B2 corresponding to an image signal of a magenta color, a laser beam B3 corresponding to an image signal of a cyan color, and a laser beam B4 corresponding to an image signal of a black color to a photoconductive drum 21 for the yellow color, a photoconductive drum 22 for the magenta color, a photoconductive drum 23 for the cyan color, and a photoconductive drum 24 for the black color, respectively.

60 65 The photoconductive drums 21, 22, 23, and 24 are arrayed substantially in the horizontal direction at fixed intervals. The

transfer belt 25 of an endless shape is provided above these photoconductive drums 21, 22, 23, and 24. The transfer belt 25 is laid over the drive roller 26, guide rollers 27, 28, and 29, and a driven roller 30. The transfer belt 25 is subjected to power from the drive roller 26 and rotates to travel in a counterclockwise direction. The guide roller 27 is provided to move up and down freely. The guide roller 27 is subjected to rotation of a cam 31 and moved to the transfer belt 25 side to displace the transfer belt 25 to the photoconductive drums 21, 22, 23, and 24 side.

Primary transfer rollers 41, 42, 43, and 44 are provided to be movable up and down in positions opposed to the photoconductive drums 21, 22, 23, and 24 across the transfer belt 25. The primary transfer rollers 41, 42, 43, and 44 are moved (lowered) to the transfer belt 25 side to bring the transfer belt 25 into contact with the photoconductive drums 21, 22, 23, and 24 and transfer visible images on the photoconductive drums 21, 22, 23, and 24 to the transfer belt 25.

Although not shown in the figure, a cleaner, a charge removing lamp, a charging unit, and a developing unit are displayed one after another around the photoconductive drum 21 (and the other photoconductive drums 22, 23, and 24 as well). The cleaner has a cleaning blade, which comes into contact with the surface of the photoconductive drum 21, and scrapes off a developing material remaining on the surface of the photoconductive drum 21 with the cleaning blade. The charge removing lamp removes electric charges remaining on the surface of the photoconductive drum 21. The charging unit applies a high voltage to the photoconductive drum 21 to charge the surface of the photoconductive drum 21 with electrostatic charges. The laser beam B1 emitted from the exposing unit 11 is irradiated on the surface of the photoconductive drum 21 subjected to the charging. An electrostatic latent image is formed on the surface of the photoconductive drum 21 by this irradiation. The developing unit supplies a developing material (a toner) of the yellow color to the surface of the photoconductive drum 21 to visualize the electrostatic latent image on the surface of the photoconductive drum 21.

Plural paper feeding cassettes 50 as paper supplying sources are provided below the exposing unit 11. A large number of pieces of paper P of types different from one another are stored in these paper feeding cassettes 50 in a stacked state. Paper feeding mechanisms 221 that feed the paper in the paper feeding cassettes 50 piece by piece from the top are provided in exit portions (on the right side in the figure) of these paper feeding cassettes 50, respectively. The paper P is taken out piece by piece from any one of the paper feeding cassettes 50 by this paper feeding mechanism 221. This paper feeding mechanism 221 for taking out paper is constituted by a pickup roller 51, a paper feeding roller 52a, and a separation roller 52b. The paper feeding mechanism 221 separates the paper P taken out from the paper feeding cassette 50 and feeds the paper to a paper conveying path 53 piece by piece.

The paper conveying path 53 extends to a paper discharge port 54 above through the driven roller 30 of the image forming unit 220. The paper discharge port 54 faces a paper discharging unit 55 leading to an outer peripheral surface of the main body 1. Conveying rollers 56 are provided near the paper feeding mechanisms 221, respectively, on a start end side of the paper conveying path 53. When paper is fed to this paper conveying path 53 by any one of the paper feeding mechanisms 221, the paper conveying path 53 conveys the paper fed to the paper discharging unit 55.

A secondary transfer roller 57 is provided, across the transfer belt 25, in a position opposed to the driven roller 30 in a midway portion of the paper conveying path 53. Registration

rollers 58 are provided in a position before the driven roller 30 and the secondary transfer roller 57 in a conveying direction. The registration rollers 58 deliver the paper P into a space between the transfer belt 25 and the secondary transfer roller 57 at timing synchronizing with a transfer operation by the transfer belt 25 and the secondary transfer roller 57. The secondary transfer roller 57 transfers, while nipping the paper P delivered from the registration rollers 58 between the secondary transfer roller 57 and the transfer belt 25 on the driven roller 30, a visible image transferred on the transfer belt 25 to the paper P and prints the visible image on the paper P. In other words, the registration rollers 58 convey the paper P to the image forming unit 220 having the transfer belt 25 and the secondary transfer roller 57 in synchronization with a printing operation of the image forming unit 220.

A heat roller 59 for heat fixing and a press-contact roller 60 in contact with this heat roller 59 are provided in a position of the paper conveying path 53 further on a downstream side than the secondary transfer roller 57. The image transferred to the paper P is fixed by the heat roller 59 and the press-contact roller 60. A paper discharging roller 61 is provided at an end of the paper conveying path 53.

Reference numeral 222 denotes an automatic duplex unit (hereinafter referred to as ADU). The ADU 222 has a paper conveying path 62 that is divided from a downstream side with respect to the image forming unit 220 on the paper conveying path 53 (the end of the conveying path 53) and joins with an upstream side with respect to the image forming unit 220 on the paper conveying path 53 (an upstream side position of the registration rollers 58). This paper conveying path 62 reverses the front and the back of the paper P for duplex printing. The paper conveying path 62 is provided with the conveying rollers 63, 64, and 65 and, in operation, switches back paper conveyed from the image forming unit 220 to the paper discharging unit 55 and joins the paper to the upstream side of the image forming unit 220. In this way, the paper P returned to the upstream side of the image forming unit 220 by the paper conveying path 62 joins with the paper conveying path 53. The paper P is delivered to the image forming unit 220 by the registration rollers 58 in synchronization with a printing operation of the image forming unit 220. Therefore, the visible image on the transfer belt 25 is transferred to the rear surface of the paper P and printed.

The paper conveying path 53 that conveys the paper fed by the paper feeding mechanism 221 to the paper discharging unit 55 is set as a main paper conveying path and the paper conveying path 62 for reversing the front and the back of the paper is set as a sub paper conveying path. This sub paper conveying path 62 comes into the operation state described above when the duplex printing is designated by a not-shown control panel or the like provided in the apparatus main body 1.

Reference numeral 223 denotes a paper type sensor, which is arranged on the upstream side with respect to the image forming unit 220 on the main paper conveying path 53 (a position further on the upstream side than the registration rollers 58) and detects a type of paper conveyed by the paper conveying path 53. FIG. 3 is schematically shows the main paper conveying path 53 section in FIG. 1 extracted and enlarged. In FIG. 3, a positional relation among the paper type sensor 223, the registration rollers 58, and the joining point on the main paper conveying path 53 is clearly shown. As this paper type sensor 223, a publicly known sensor that discriminates a paper type by detecting the thickness and luminous transmittance of paper only has to be used.

In an example in FIG. 1, the two paper feeding cassettes 50 are provided as paper feeding sources. However, it goes with-

out saying that the number of paper feeding cassettes **50** may be three or more. Besides, although not shown in the figure, a manual paper feeding mechanism (hereinafter referred to as SFB) and a large capacity paper feeder (hereinafter referred to as LCF) capable of stacking and feeding several thousand pieces of paper are used. Paper feeding paths from the SFB and LCF also join with the main paper conveying path **53**. The paper type sensor **223** is arranged further on the downstream side than a joining point of the paper feeding paths from the paper feeding sources SFB and LCF. Therefore, it is possible to detect, with one paper type sensor **223**, all types of paper fed from the respective paper feeding sources and conveyed on the main paper conveying path **53**.

A cleaner **36** is provided across the transfer belt **25** in a position opposed to the driver roller **26** of the image forming unit **220**. This cleaner **36** has a cleaning blade **36a**, which comes into contact with the transfer belt **25**, and scrapes off a developing material remaining on the transfer belt **25** with the cleaning blade **36a**. Hooks **71**, **72**, **73**, and **74** are provided near the primary transfer rollers **41**, **42**, **43**, and **44**. These hooks **71**, **72**, **73**, and **74** can engage with shafts of the primary transfer rollers **41**, **42**, **43**, and **44** and lift the shafts while rotating and move the primary transfer rollers **41**, **42**, **43**, and **44** in an upward direction in the figure. It is possible to set a full color mode, a fully separated mode, and a monochrome mode according to which ones (one) of the primary transfer rollers **41**, **42**, **43**, and **44** are lifted.

A control circuit for the apparatus main body **1** will be explained using FIG. 2. Reference numeral **200** denotes a main controller. A control panel controller **201**, a scan controller **202**, and a print controller **210** are connected to the main controller **200**. The main controller **200** collectively controls the control panel controller **201**, the scan controller **202**, and the print controller **210**.

The scan unit **203** is connected to the scan controller **202**. As described above, the scan unit **203** is constituted by the carriage **4**, the exposure lamp **5**, the reflecting mirrors **6**, **7**, and **8**, the lens block for magnification **9**, the CCD **10**, and the like and optically scans an image of an original placed on the original stand **2**.

The print controller **210** is connected to the paper type sensor **223** and is connected to a ROM **211** for control program storage, a RAM **212** for data storage, the print engine **213**, the process unit **214**, and a conveying unit **215**, respectively. As described above, the print engine **213** is constituted by the exposing unit **11** and the like. As described above, the process unit **214** is constituted by the photoconductive drums **21**, **22**, **23**, and **24**, the transfer belt **25**, the drive roller **26**, the transfer-roller driving unit, and the like. The conveying unit **215** is constituted by conveying mechanisms for the paper **P**, driving circuits for the conveying mechanisms, and the like in the paper conveying paths **53** and **62**.

As shown in FIG. 2, the print controller **210** has a condition setting unit **210a**, a process control unit for image formation **210b**, and a paper-conveying-path control unit **210c** as functions.

The condition setting unit **210a** optimally sets conditions for the image forming unit **220** (the process unit **214** in FIG. 2 is equivalent to the image forming unit **220**) in accordance with a detection result of the paper type sensor **223**.

The process control unit for image formation **210b** controls start timing of the image forming process in the image forming unit **220**. The process control unit for image formation **210b** controls start timing of the image forming process according to whether a type of paper fed from the paper feeding cassette **50** to the paper conveying path **53** by the paper feeding mechanism **221** is detected by the paper type

sensor **223**. When a paper type is not detected yet, the process control unit for image formation **210b** starts the image forming process awaiting a detection result by the paper type sensor **223**. On the other hand, when a paper type is already detected (for example, when remaining pieces of paper are fed from the same cassette), the process control unit for image formation **210b** can start the image forming process without awaiting paper type detection.

The paper-conveying-path control unit **210c** has a function 10 of controlling, when the paper **P** is fed to the paper conveying path **53** by the paper feeding mechanism **221**, the paper conveying path **53** to convey this paper to the paper discharging unit **55** and controlling the registration rollers **58** to convey paper, which is conveyed by the paper conveying path **53**, to 15 the image forming unit **220**, in which the image forming process is started, in synchronization with a printing operation of the image forming unit **220**.

In the constitution described above, for example, when one 20 of the paper feeding cassettes **50** stores one new paper type and is set in the apparatus main body **1**, the paper type of the paper **P** stored in this paper feeding cassette **50** is not detected by the paper type sensor **223** yet. In this state, when a paper feeding command is issued to perform printing on the paper in the paper feeding cassette **50**, in which this undetected paper type is stored, the paper feeding mechanism **221** corresponding to this paper feeding cassette **50** feeds the paper **P** in the paper feeding cassette **50** to the paper conveying path **53** piece by piece.

The paper-conveying-path control unit **210c** causes the 30 conveying roller **56** to rotate and convey the paper **P** fed to the paper discharging unit **55**. In the middle of this conveyance, a paper type of the paper **P** is detected by the paper type sensor **223**. After passing through the paper type sensor **223**, the paper **P** being conveyed temporarily stops in the portion of the 35 registration rollers **58** located upstream of the image forming unit **220**.

In this state, the condition setting unit **210a** optimally sets, 40 in accordance with a detection result of the paper type sensor **223**, conditions for an image forming process of the image forming unit **220** (the process unit **214** in FIG. 2) to match the paper type detected. Since the image forming unit **220** executes an image forming process for forming an image based on image data and transferring the image to paper being conveyed by the transfer belt **25**, the secondary transfer roller **57**, and the like and printing the image, the condition setting unit **210a** optimally sets conditions for the image forming process according to a paper type.

Since a paper type of the paper fed to the paper conveying path **53** is not detected yet as described above, the process 50 control unit **210b** starts the image forming process awaiting a detection result by the paper type sensor **223**. After this, the paper-conveying-path control unit **210c** controls the registration rollers **58** to deliver the paper **P** temporarily stopped before the registration roller **58** to the image forming unit **220**, 55 in which the image forming process is started, in synchronization with a printing operation. Therefore, the image forming unit **220** transfers the image formed on the basis of the image data to the paper **P** delivered thereto by the registration rollers **58** and prints the image. The image transferred is 60 heated and fixed by the heat roller **59** for heat fixing and the press-contact roller **60**. After the fixing, the paper printed is discharged from the paper discharge port **54** to the paper discharging unit **55** by the paper discharging roller **61**.

A case in which a paper feeding command is issued for 65 paper stored in the same paper feeding cassette **50** as the paper, the paper type of which is detected as described above, will be explained. In this case, since the paper fed this time is

fed from the same paper feeding cassette 50 as the paper, the paper type of which is already detected by the paper type sensor 223, the process control unit 210b determines that the paper is paper of the same type. Therefore, it is possible to start the image forming process without awaiting paper type detection. The process control unit 210b starts the image forming process at a point when the paper is fed to the paper conveying path 53 without awaiting a detecting operation by the paper type sensor 223. In this case, the paper-conveying-path control unit 210c controls the registration roller 58 to deliver the paper to the image forming unit 220 in synchronization with a printing operation of the image forming unit 220. At this point, since the image forming process is already started, the paper is immediately delivered to the image forming unit 220 without being kept waiting a long time before the registration rollers 58. Printing based on the image data is promptly performed.

As described above, in the image forming apparatus according to the first embodiment of the invention, a paper type of paper, a paper type of which is not detected yet, is detected by the paper type sensor 223 provided in the middle of the paper feeding and conveying process. This paper type detection is incorporated in an image forming algorithm and image formation start timing is associated with this paper type detection. Consequently, unlike in the past, it is unnecessary to perform partial paper feeding for paper type detection prior to an original paper feeding command. Therefore, an operation for returning paper once delivered to a sensor section to a paper storing unit to prevent the paper from blocking a course of paper conveyed from another paper feeding stage is not required for a paper feeding operation for the purpose of paper type detection. Since it is also unnecessary to arrange a sensor near the paper feeding mechanism, one sensor only has to be provided in common to respective paper feeding sources on a paper conveying path. Therefore, a structure is simplified and a stable operation is obtained.

As shown in FIG. 3, the one paper type sensor 223 is arranged in a position further on the upstream side than the registration rollers 58 on the main paper conveying path 53 and provided in common to the respective paper feeding sources. However, the invention is not limited to such a constitution and the paper type sensor 223 may be arranged as shown in FIG. 4. The paper type sensor 223 may be arranged between the paper feeding mechanism 221 for each of the paper feeding cassettes 50 as the paper feeding sources and the paper conveying path 53.

With such a constitution, the paper type sensors 223 are necessary by a number equivalent to the number of paper feeding sources. However, since it is possible to detect a paper type of fed paper at an initial stage of paper feeding and conveyance, it is possible to bring forward start timing of the image forming process and obtain high performance.

What is claims is:

1. An image forming apparatus comprising:
a paper stacker configured to stack a first sheet and a second sheet;
an image forming unit configured to form an image on the first sheet, and configured to form an image on the second sheet after forming the image on the first sheet;
a sheet type sensor configured to sense the first sheet on a path between the paper stacker and the image forming unit to detect a type of the first sheet;
a condition controller configured to set a condition for the image forming unit in accordance with the type of the first sheet; and
a process controller configured to control the image forming unit to start to form the image on the first sheet after

waiting for the condition controller to complete to set the condition, and configured to control the image forming unit to start to form the image on the second sheet without changing the condition in accordance with a type of the second sheet.

2. An image forming apparatus according to claim 1, wherein the sheet type sensor senses thickness of a sheet to distinguish a type of the sheet.

3. An image forming apparatus according to claim 1, wherein the sheet type sensor senses light transmittance of a sheet to distinguish a type of the sheet.

4. An image forming apparatus according to claim 1, wherein

the image forming unit includes:

an exposing unit configured to perform exposure corresponding to an image signal; and

a process unit including a photoconductive drum on which an electrostatic latent image is formed by the exposing unit, a developing unit configured to develop the electrostatic latent image formed on the photoconductive drum into a visible image with toner, a transfer unit configured to transfer the visible image from the photoconductive drum onto a sheet, and a fixing unit configured to fix the visible image on the sheet, and

the condition controller controls the process unit of the image forming unit.

5. An image forming apparatus according to claim 4, wherein the condition is an amount of toner supplied to the photoconductive drum.

6. An image forming apparatus according to claim 4, wherein the condition is a transfer condition for the transfer unit that transfers the visible image formed on the photoconductive drum onto a sheet.

7. An image forming apparatus according to claim 4, wherein the condition is a fixing condition for the fixing unit that fixes the image transferred on the sheet.

8. An image forming apparatus comprising:

a plurality of paper stackers, each of which is configured to stock a first sheet and a second sheet;
an image forming unit configured to form an image on the first sheet, and configured to form an image on the second sheet after forming the image on the first sheet;
a common path for sheet conveyance configured by joining paths from outlets of the paper stackers, the common path leading to the image forming unit;

a sheet type sensor configured to detect a type of the first sheet on the paths between the paper stackers and a joining point to the common path;

a condition controller configured to set a condition for the image forming unit in accordance with the type of the first sheet; and

a process controller configured to control the image forming unit to start to form the image on the first sheet after waiting for the condition controller to complete to set the condition, and configured to control the image forming unit to start to form the image on the second sheet without changing the condition in accordance with a type of the second sheet.

9. An image forming apparatus according to claim 8, wherein the sheet type sensor senses thickness of a sheet to distinguish a type of the sheet.

10. An image forming apparatus according to claim 8, wherein the sheet type sensor senses light transmittance of a sheet to distinguish a type of the sheet.

11. An image forming apparatus according to claim 8, wherein

11

the image forming unit includes:

an exposing unit configured to perform exposure corresponding to an image signal; and

a process unit including a photoconductive drum on which an electrostatic latent image is formed by the exposing unit, a developing unit configured to develop the electrostatic latent image formed on the photoconductive drum into a visible image with toner, a transfer unit configured to transfer the visible image from the photoconductive drum onto a sheet, and a fixing unit configured to fix the visible image on the sheet, and

the condition controller controls the process unit of the image forming unit.

12. An image forming apparatus according to claim 11, wherein the condition is an amount of toner supplied to the photoconductive drum.

13. An image forming apparatus according to claim 11, wherein the condition is a transfer condition for the transfer unit that transfers the visible image formed on the photoconductive drum onto a sheet.

14. An image forming apparatus according to claim 11, wherein the condition is a fixing condition for the fixing unit that fixes the image transferred on the sheet.

15. A control method of an image forming apparatus comprising:

feeding, one by one, a first sheet and a second sheet stocked in a paper stacker onto a path for sheet conveyance leading to an image forming unit;

detecting a type of the first sheet with a sheet type sensor on a path between the paper stacker and the image forming unit;

5

10

20

25

30

12

setting a condition for the image forming unit by a condition controller in accordance with the detected type of the first sheet;

starting an image forming process of the image forming unit after waiting for the setting of the condition by the condition controller upon the first sheet being fed onto the path and subjected to image formation by the image forming unit; and

starting the image forming process of the image forming unit without changing the condition in accordance with a type of the second sheet upon the second sheet being fed onto the path and subjected to image formation by the image forming unit.

16. A control method according to claim 15, wherein the sheet type sensor senses thickness of a sheet to distinguish a type of the sheet.

17. A control method according to claim 15, wherein the sheet type sensor senses light transmittance of a sheet to distinguish a type of the sheet.

18. A control method according to claim 15, wherein the condition controller sets an amount of toner supplied to a photoconductive drum of the image forming unit on the basis of the detected type of the sheet.

19. A control method according to claim 15, wherein the condition controller sets a transfer condition for a transfer unit that transfers a visible image formed on a photoconductive drum of the image forming unit onto a sheet on the basis of the detected type of the sheet.

20. A control method according to claim 15, wherein the condition controller sets a fixing condition for a fixing unit that fixes an image transferred on a sheet of the image forming unit on the basis of the detected type of the sheet.
